HUBERT C. MORRIS, OF ALBANY, OREGON.

METHOD OF MAKING DOORS.

Application filed May 3, 1928. Serial No. 274,952.

My invention relates to a method of making doors, and is particularly related to a method of making panel doors, wherein the panel is made up of a plurality of units assembled into a panel in advance of the assembly of the door, so that a panel unit can be made to a predetermined size to fit the opening in the door provided for that purpose, at the time of the assembly of the door unit.

In the manufacture of doors of this character, it is essential to provide means for the expansion and contraction of the panel, without the disrupting of the door structure, when the expansion occurs due to the absorption of moisture by the panel structure.

I am aware that a routed groove has been provided within the adjacent encompassing members, of the panel, to which the panel is associated, and that the expansion of the panels may be compensated by the same entering into the grooves provided for that purpose. It has been my observation that as the expansion and contraction of the panel as a whole occurs, the fastenings passing through the diagonal bracing into the individual units of the panel become loose, that the panel gets out of shape and many times the bracing becomes loose, and that the expansion and contraction is not uniform through the individual units, so that cracks and openings occur between the individual unit elements of the panel even though a tongue and groove connection is provided between the adjacent units or elements. The uneven shrinkage does not give uniform results. To prevent this occurring within the panel I provide means in the assembly of the door panel whereby an expansion and contraction of the individual units comprising the panel is not transferred from one to the other thus causing a movement of the adjacent units thereto. Instead I provide a limited space adjacent the walls of the companion panel elements so that the shrinkage of the panel elements is not transferred from one to the other, thus effectively preventing an expansion and contraction of the panel as a whole.

The primary object of my invention consists in the assembly of a door having a panel disposed therein, in which said panel being comprised of a plurality of individual units in spaced relationship with each other, said spacing being sufficient only for the compensation of shrinkage and swelling and the overall dimension being made to a predetermined width. A diagonal bracing being placed across the panel and the individual units comprising the panel being secured thereto.

A further object of my invention consists in a method of constructing doors that result in a door that will give uniformly satisfactory results over long periods.

With these and incidental objects the invention consists in certain novel features of application and methods of procedure, the essential elements of which are set forth in the appended claims, and a preferred form of embodiment of which is hereinafter shown with reference to the drawings which accompany and form a part of this specification:

My methods may be successfully carried out through the utilization of mechanism illustrated in the accompanying drawings, in which:

Fig. 1 is a top, plan view of an assembly frame into which the panels may be assembled in advance of the same being placed within the door during the assembly of the door.

Fig. 2 is a top, plan view, partially in section of a door made by my new and improved methods.

Fig. 3 is a cross section view, taken on line 3—3 of Fig. 2, looking in the direction indicated.

Fig. 4 is a fragmentary, cross section view, taken on line 4—4 of Fig. 2, looking in the direction indicated, the same being made to illustrate the placing of the outside unit of the panel to the full depth of the groove disposed adjacent the side and end walls of the panel and within the panel frame.

Fig. 5 is a fragmentary, cross section view, taken on line 5—5 of Fig. 1, looking in the direction indicated.

Fig. 6 is a fragmentary, cross section view, taken on line 6—6 of Fig. 1, looking in the direction indicated.

Like reference characters refer to like parts throughout the several views.

The door to be made consists in its essential elements of side members 1 and 2 and bottom and center rails 3 and 4. These four elements form a frame into which the panel is placed. A relatively deep groove is formed on the inner edge of these four units into which the peripheral edge of the panel is made to fit and which bounds the same and maintains the panel in place and position within the bounding frame structure. The panel is formed of a plurality of units 5 that in preferred form are tongued and grooved so that they are held together. In the assembly of these units in a relatively loose condition, any swelling of each individual unit that occurs will not be transmitted to the next unit as the spacing of each from the other is sufficient only to compensate for such swelling.

Diagonal bracings 6 and 7 are disposed across the panel and engage the meeting edges of the side members and the bottom and central rails to brace and stiffen the door when the same is completed. In the forming of the panel the same is done within a frame 8 having corner angle braces 9, so that when the panel is constructed it will be of a size to precisely fit that of the space provided to receive the same. Disposed within the frame 8 are a plurality of spacing elements 10 adapted to upwardly extend from the bottom 11 of the frame 8 and to engage between the units 5 forming the panel, as illustrated at 12 and 13 in Fig. 5. This spaced relationship between adjacent surfaces of the panel units 5 is sufficient for the swelling only and the primary purpose and intention of which is to prevent the expanding of the frame structure surrounding the panel. The corner braces 9 have added spaces 14 disposed in each corner which is of a thickness or depth precisely that of the depth of the groove 15 disposed within the frame structure so when the panel is completed the units of the panel entering the groove 15 will extend to the bottom 16 thereof and the spacing of the edges of the diagonal member elements 6 and 7 will be spaced a sufficient distance from the element of the units, as illustrated at 17 in Fig. 1 to permit of the entry of the extending edge of the outer panel units sufficiently to extend to the depth of the groove 15. When the panel has been assembled within the frame with the units 5 in spaced relationship the diagonal bracing is then placed thereupon within the frame and is secured to each unit 5 forming the panel so that the same will be relatively fixed, as the same relates to the diagonal bracings. In doing so the contraction and expansion of each of the

units 5 is not transmitted to the adjacent units and therefore the relation of the center line of each unit 5 remains substantially the same as it relates to the bracing. Doors made in this manner remain relatively tight over long periods; the units 5 remain relatively fixed and the shrinkage and expansion of the same is not apparent excepting on close inspection. The panel may then be inserted within the door and the remaining side members and the bottom rail be inserted therein, placed in position after which the same may be secured together by any suitable fastening means, as by gluing or doweling or any other suitable and satisfactory means.

When the panel has been assembled within the frame and the diagonal bracing has been placed thereupon, said bracing elements being made to a precise length and placed in a precise position upon the panel and within the frame, the panel is then assembled in the door frame as the door is finally assembled. The door is then tightened up in assembly and the diagonal bracings are stressed sufficiently to brace the door into a commercial and usable structure and one that may be used over relatively long periods, without losing its shape or becoming loose or becoming racked through use.

In the final assembly of the door, the bottom rail of the door is made to move endwise of the side members and to engage one of the ends of the panels and to maintain the panel in a relatively tight relation with the bottom and center rails thus further stiffening the panel structure and maintaining each of the panel elements in placed position.

I have observed in the manufacture of doors that if the diagonal bracing is made to engage the side members and the bottom and central elements in advance of the bottom and central elements engaging the individual panel units, that an initial stress will be placed in the diagonal bracing elements resulting in tightening the door up during assembly that is important and gives the door a longer life. This is primarily accomplished by applying compression to the end units of the door during assembly. End movement of the bottom rail is provided for by the placing of the mortise within the side members to receive the tenons of the bottom rail sufficiently long to permit of a movement of the bottom rail lengthwise of the side rails when the assembling end pressure is applied to the door.

While the form of mechanism herein described may be successfully used in the carrying out of my method, I do not wish to be limited to the specific form of mechanism herein shown and described as any form of mechanism may be used that is adapted to the carrying out of my method, all coming within the scope of the claims which follow.

What I claim is:

1. In the manufacture of doors, having a recessed frame for the retention of a panel therein, said panel being composed of a plurality of strips in spaced relation and secured together by diagonal bracing, the method of assembling said panel consisting in the placing of the strips in spaced relation within a frame of a predetermined dimension to form a panel of a predetermined size, then locating the diagonal bracing and the fastening of the same to each panel element.

2. In the manufacture of doors, having a frame with a recessed groove in its inner edge for the retention of a panel of a predetermined overall dimension therein, the peripheral edges of said panel extending the full depth of the said groove and the said panel being composed of a plurality of elements disposed in relatively spaced relation within the panel, diagonal bracing elements disposed upon the panel and secured thereto, the method of assembling said panel consisting in the placing of the panel elements within a frame of a predetermined size to completely fill the frame to a precise position upon the panel and the fastening of the diagonal elements to each of the panel elements.

3. In the manufacture of doors, having a frame comprising side members and a bottom and a central rail, said frame having a groove disposed on its inner edge for the retention of a panel therein, said panel being an overall dimension to precisely fill the opening within the frame to the full depth of the groove and composed of a plurality of elements in spaced relation with each other, and having diagonal bracings disposed upon the panel and secured thereto, the method of assembling the panel consisting of placing the panel elements in relatively spaced relation upon a frame and filling the same to a precise overall dimension of height and width, the placing of diagonal bracing elements upon the panel elements within the frame and the fastening of the diagonal bracings and of the panel elements together.

4. In the manufacture of wooden doors having a frame comprising side members and a bottom and a central frame to form an opening of a predetermined size therein, and said frame elements having a groove formed on their inner edges of the opening thus formed, a panel of an overall dimension of the opening formed within the frame, said panel being formed of a plurality of panel elements arranged in parallel and each being in spaced relation with the adjacent panel elements, such space being sufficient only for any normal swelling that may occur within the panel element, and diagonal bracings disposed upon the panel elements and secured to each of the panel elements, the method of assembling the panel consisting in placing the panel elements within a frame of a predetermined size,

said panel elements being in spaced relation with each other sufficient to compensate for the normal swelling of the panel elements and the placing of diagonal bracing upon the panel of a length to fit into the corners of the door frame forming the opening for the panel and the fastening of the diagonal bracings and the panel together and to each other.

5. In the manufacture of doors, having a panel forming a substantial area of the door, and having a routed groove disposed within the side frames and in the bottom rail and in the central rail for the retention of the panel therein, said panel being composed of a plurality of elements in slidable relation with each other, diagonal bracing for the panel elements and secured to the panel elements, the outer periphery of the assembled panel filling the full extent of the groove disposed in the door frame when the door is assembled, the method of assembling said panel and door consisting in the assembling of the panel elements within a frame and in spaced relation and the placing of the diagonal bracing on the panel elements in the frame and the fastening of the same together while in the frame, the assembling of the panel within the door frame structure and the application of end pressure to the door structure after assembly and the fastening of the frame together before the release of the end pressure.

6. In the manufacture of doors, having a panel formed of a plurality of panel elements in slidable contact and in spaced relation with each other but relatively fixed to the side members of the door when assembled, the frame of the door comprising side members and cross rails, a groove disposed within the door frame for the reception of the panel therein to the full depth of the groove, a panel having diagonal bracings disposed thereupon and secured to the panel elements, the method of assembling the door consisting in the pre-assembly of the panel and the diagonal bracing with the panel elements in spaced relation with each other and each panel element secured to the diagonal bracing, the rim of the panel outwardly extending from the end terminals of the diagonal bracings slightly less than the depth of the groove so that a stress will be placed within the bracings when the panel is assembled within the frame and extended to the full depth of the groove, the assembly of the panel within the frame, and the application of end pressure to the door during assembly and the final fastening of the door together.

7. In the manufacture of doors, having a panel made up of a plurality of vertical elements in slidable relation with each other, but substantially fixed relative to the door frame, said panel adapted for fixed engagement within a panel groove disposed within the panel frame, diagonal bracings disposed upon the panel elements and secured thereto,

the panel rim extending beyond the ends of the diagonal bracing elements slightly less than the depth of the groove for the reception of the panel rim therein, the method of assembly consisting in the assembly of the panel and the diagonal bracing within a frame to a precise dimension, the assembly of the panel

within the frame, the application of end pressure to the door to press the panel to intimate end engagement with the cross rails of the door and the final fastening of the door together before the pressure is released. ¹⁰
